UNITED STATES PATENT OFFICE.

JOHN EVANS, OF ETNA, ASSIGNOR OF ONE-HALF TO SPANG, CHALFANT & CO., OF ALLEGHENY CITY, PENNSYLVANIA.

PUDDLING-FURNACE.

SPECIFICATION forming part of Letters Patent No. 270,184, dated January 2, 1883.

Application filed February 15, 1882. (No model.)

To all whom it may concern:

Be it known that I, JOHN EVANS, of Etna, in the county of Allegheny and State of Pennsylvania, have invented a new and useful Improvement in Puddling-Furnaces; and I do hereby declare the following to be a full, clear, and exact description thereof.

My invention relates to an improvement in that class of puddling-furnaces in which hydrocarbon gas is used as fuel; and it consists in the arrangement and construction of the interior of the furnace for the purpose of obtaining a thorough and perfect combustion of the gas, so as to create an intense heat over the hearth of the furnace.

My invention is described as applied more especially to puddling-furnaces; but it may be adapted to heating and other furnaces.

I will now describe my invention, so that others skilled in the art may manufacture and use the same, reference being had to the accompanying drawings, forming a part of this specification, in which—

Figure 1 is a vertical longitudinal section of my improved puddling-furnace. Fig. 2 is a detailed sectional view of the vertical wall *h* and perforated gas-supply pipe embedded therein.

Like letters refer to like parts wherever they occur.

In the drawings, *a* represents an air-flue which extends from the front to the rear end of the furnace. Above the flue *a* is another flue, *d*, which extends along and under the hearth *e*, being separated from the flue *a* by the division-wall or false bottom *b*, to the front end of the furnace, where it opens into the flue *f*. The flues *a* and *d* communicate with each other by the opening *c* at the rear end of the furnace. At the rear side of the flue *f* are two walls, *g* *h*, having a space, *i*, between them. Inside of this space *i*, set in the side of the wall *h*, is a gas-supply pipe, *k*, having perforations extending its length, which discharge into the space. The wall *h* should be somewhat higher than the wall *g*. Beyond the wall *h* is a dependent wall *l*, extending downward into the chamber *l'* from the top of the furnace. The bridge-wall *m* divides the chamber *l'* from the hearth *e*.

The operation is as follows: The inflowing

air passing through the flues *a* and *d* becomes thoroughly heated and mingle with the gas which is delivered by the perforated gas-pipe, is spread and deflected by the wall *g*, and passes out of the space *i* in a sheet which mingle with the incoming air in the chamber *l'*. The wall *h* causes the gas and air to pass sufficiently high to strike against the pendent wall *l*, which deflects the gas and air downward into the chamber *l'*, where a low combustion takes place and the gas and air become mingled, so that they burn with a clear flame, giving out intense heat over the hearth *e*, where they are entirely consumed, and merely the products of combustion pass out through the neck and stack, the destruction of which by hot flames is thereby avoided.

The advantages of my invention are: First, the air is thoroughly heated before coming into contact with the gas, which renders the combustion more perfect; second, the gas escaping from the opening *i*, which extends across the furnace, becomes heated by and thoroughly mingled with the heated air; third, the wall *h*, pendent wall *l*, and bridge-wall *m* retard the flow of the air and gas and cause them to be thoroughly mingled, so that the combustion over the hearth *e* is complete, and an intense heat is created at that point; and, fourth, the combustion over the hearth being complete, or nearly so, the neck of the furnace is not apt to burn out, as heretofore.

I am aware that heretofore, in the construction of this class of furnaces, false bottoms have been used to form return-flues for heating the incoming air; that vertical walls have been used to divide the combustion-chamber into principal and auxiliary combustion-chambers; that perforated pipes have been used to deliver the incoming combustible gases; and that generally the several elements are not novel *per se*, or in combinations of two or more; but I am not aware that the several elements have been heretofore arranged to coact, as herein set forth and claimed; and therefore,

Having thus described my invention, what I claim, and desire to secure by Letters Patent, is—

1. In a gas-furnace, the combination, with the working-chamber, of a false bottom or di-

vision-wall arranged below the same to form a return-flue for the admission of air, a vertical wall for forming an auxiliary combustion-chamber in front of the working-chamber, and 5 a perforated gas-supply pipe arranged to deliver into the air-flue, substantially as and for the purpose specified.

2. In a gas-furnace, the combination, with the working-chamber, of a vertical wall which 10 forms an auxiliary combustion-chamber, a pendent deflecting-wall arranged over the auxiliary combustion-chamber, a perforated gas-supply pipe, and a division-wall or false bottom arranged below the working-chamber or 15 hearth to form a return-flue for the admission

of air, substantially as and for the purpose specified.

3. In a gas-furnace, the combination, with the working-chamber, of the pendent wall *l*, the vertical walls *g h*, perforated gas-supply pipe *k*, and false bottom *b*, the parts relatively arranged to form the return-flue *a d*, flue *f*, and auxiliary combustion-chamber *l'*, substantially as and for the purpose specified.

In testimony whereof I have hereunto set my hand this 10th day of February, A. D. 1882.

JOHN EVANS.
